UNITED STATES PATENT OFFICE.

PERCY J. ANDREWS, OF WARWICK, RHODE ISLAND.

CYLINDER LINING.

Application filed July 27, 1922. Serial No. 577,954.

To all whom it may concern:

Be it known that I, PERCY J. ANDREWS, a citizen of the United States, residing at Warwick, in the county of Kent and State 5 of Rhode Island, have invented certain new and useful Improvements in Cylinder Linings, of which the following is a specification.

This invention relates to improvements in 10 the construction of linings for the bores of engine cylinders, and has for its object to provide a lining of this character which may be formed to slide with an easy fit into the bore of the cylinder and be bound therein in 15 such a way as to permit a uniform expansion of the lining throughout its length.

A further object of the invention is to so construct this lining and its locking member that the same may be withdrawn from 20 the head of the cylinder and a fresh one positioned without being obliged to remove the pistons from the cylinder and so obviate the necessity of removing the crank case and crank shaft from the engine casing.

25 A still further object of the invention is to provide means for locking the sleeve or lining against rotation after having once been set into the cylinder.

The invention further consists in beveling 30 the entering end of the sleeve or lining from its inner wall outwardly so as to engage, contract and reposition the piston rings when the pistons are in the cylinder.

With these and other objects in view, the 35 invention consists of certain novel features of construction, as will be more fully described, and particularly pointed out in the appended claims.

In the accompanying drawing:

40 Figure 1 is a sectional side elevation showing a cylinder with my improved bushing mounted therein.

Figure 2 is an end view of the cylinder with the cylinder-head removed.

45 Figure 3 is a side elevation of the lining, locking nut.

Figure 4 is a side elevation of the lining.

It is found in practice of advantage to so position a lining in an engine cylinder that

50 it may be readily removed and replaced by a fresh one after having been worn, and to be able to do this from the outer end of the cylinder, without being obliged to remove the crank and casing from their set positions.

55 It is also found of advantage to so construct

the cylinder-lining-sleeve that it may expand uniformly throughout its length under high working temperature, and the following is a detailed description of the means by which these advantageous results may be 60 accomplished:

With reference to the drawings, 10 designates the usual cylinder which may be of any suitable construction, the same being provided, preferably, with a shoulder 11 at 65 the inner end of its bore.

This shoulder is preferably beveled from its outer edge inwardly for the purpose presently described, and the outer end of this cylinder is preferably threaded as at 12 to 70 receive a threaded nut 13, which nut is provided at its outer edge with small holes 14 to receive and be operated by the usual spanner wrench.

The cylinder lining comprises essentially 75 a sleeve 15, the external and internal diameters of which are preferably uniform throughout its length.

The ends 16 and 17 of this tubular lining are preferably beveled from their inner surfaces outwardly, the lower edge being adapted to fit into the complementary groove in the shoulder 11, while the upper edge 16 is engaged by the inner end of the tubular nut 13, which is also correspondingly beveled, 80 whereby when this nut is screwed into position against the upper end of the lining it forces the same down against the shoulder 11 and has a tendency to spread or expand the ends of the lining against the walls of 85 the cylinder whereby by this construction the working head to which the lining is subjected causes the same to expand uniformly 90 throughout its length.

It is found in practice necessary to provide 95 means for positively preventing the sleeve from rotating in the cylinder, as the action of the piston, while working continually in the same path in the cylinder, serves to wear the rings to nicely fit therein, 100 and if the lining were permitted to rotate after having been worn to fit the pistons and their rings, the rings would always leak and the cylinder lose compression.

To obviate this difficulty, and positively 105 prevent the lining from rotating after having been set in the cylinder, I drill a hole 19 down into the edge of the cylinder between its inner wall and the outer wall of the nut and lining and insert a key or pin 110

20 therein, which serves to positively lock both the nut and the lining against rotation in the cylinder.

5 By my improved construction it will be seen that when it is desired to reline the cylinder it is only necessary to move the head 21 and engage the projecting outer end 22 of the locking pin to withdraw the same after which the spanner wrench may be employed to unscrew the nut and the lining which is loosely mounted in the cylinder may then be withdrawn and a fresh one positioned to take its place and all without removing the pistons, the crank shaft or crank 10 casing from the engine head.

15 The device is extremely simple and practical in construction and effective in its operation and by its use the bore of a cylinder may be readily renewed at the minimum expense and that without re-boring and oversizing the pistons, which is found in practice to be injurious to the engine as such oversizing gives to the engine a greater power than the parts driven by it were designed 20 originally to stand. Therefore it is better to renew the lining of the cylinder with the original diameter than to re-bore for a larger size.

25 The foregoing description is directed solely towards the construction illustrated, but I desire it to be understood that I reserve the privilege of resorting to all the mechanical changes to which the device is susceptible, the invention being defined and 30 limited only by the terms of the appended claims.

I claim:

35 1. The combination with an engine cylinder having a bore with inwardly projecting means at its lower end, of a lining for the bore of said cylinder removable from its upper end and resting upon said means, a tubular nut threaded into the upper end of said cylinder for binding said lining therein against said means, and means for locking both the nut and the lining against rotation in said cylinder,

2. The combination with an engine cylinder having a bore with a shoulder near its lower end, of a lining for the bore of said cylinder comprising a tubular member of a length less than that of the cylinder bore removable from the upper end of the cylinder and resting upon said shoulder, and a tubular nut threaded into the upper end of the cylinder bore for binding said lining against said shoulder.

3. The combination with an engine cylinder having a bore with a shoulder near its lower end, of a removable lining for the bore of said cylinder, comprising a tubular member of a length less than that of the cylinder bore, the walls at the opposite ends of said lining being beveled outwardly from their inner surfaces, and a tubular nut threaded into the upper end of said cylinder bore for exerting an expanding and binding pressure on said lining against said shoulder.

4. The combination with an engine cylinder, of a removable lining for the bore of said cylinder, beveled outwardly from its inner surface at its ends, the bore of the cylinder having an inwardly-beveled shoulder adjacent its lower end, and a tubular nut threaded into the upper end of the cylinder beveled on its end to fit that in the end of the lining for binding the lining against said shoulder.

5. The combination with an engine cylinder, of a removable lining for the bore of said cylinder beveled outwardly from its inner surface at its ends, the bore of the cylinder having a shoulder with an inwardly-beveled annular recess adjacent its lower end, and a tubular nut threaded into the upper end of the cylinder having a beveled edge to engage that of the lining to bind the same against said shoulder, and means in the cylinder for locking both the nut and sleeve against rotation after being bound in position.

In testimony whereof I affix my signature.
PERCY J. ANDREWS
